MACHINE FOR PRESSING GROOVES IN
PASTEBOARD SHEETSArthur Konrad Anders Johansson,
Goteborg, SwedenApplication February 8, 1945, Serial No. 576,880
In Sweden February 3, 1944

1 Claim. (Cl. 93—58.1)

1

This invention relates to machines for pressing grooves in pasteboard sheets and more particularly to machines of that character where the grooves are formed by rollers. Such sheets are used for the manufacture of pasteboard boxes. The sheet, being provided with grooves crossing each other, is bent along the grooves to form the bottom, sides and top of the box. By the manufacture of these boxes it has been found that the pasteboard will burst in the grooves when the thickness of the sheet exceeds above a certain value for instance above $\frac{1}{8}$ of an inch. The difficulty to obtain faultless grooves will increase still much more when two or more parallel grooves are made in the sheet at the same time.

The main object of the invention is to provide a machine by which faultless grooves can be made in thick pasteboard sheets deep enough for the easy bending of the sheet to form a box.

Another object of the invention is to provide a machine with guiding means to hold the sheet in a suitable form when the sheet is fed through the machine.

A still further object of the invention is to provide a machine with rollers and with adjusting means for these rollers to form grooves of different depth in the sheet.

The invention further consists in the several novel features of construction and combination of parts hereinafter fully set forth and claimed.

The invention is clearly illustrated in the drawings accompanying this specification in which:

Figure 1 is a vertical cross section of the machine;

Fig. 2 is an end elevation view of the machine;

Fig. 3 is a magnified detail fragmental section of the driving means; and

Fig. 4 is a similar magnified detail fragmental section of the driving means in another embodiment.

In the embodiment shown in Fig. 1 of the drawings two pairs of rollers 1, 2 and 3, 4 are arranged the one pair after the other, whereat the rollers 1 and 3 are placed above the rollers 2 and 4, the roller 1 coacting with the roller 2 and the roller 3 coacting with the roller 4. The rollers 1 and 3 are provided each with a cam 40 and the rollers 2 and 4 each with a corresponding slot 41 adapted to form the grooves in the pasteboard sheets which are to be fed through the machine between the rollers.

The upper rollers 1 and 3 are free rotating on still standing shaft pins 6 which are turnably arranged in bearings 7, 8 in an upper slide 9 displaceable along guides 10 in the cross direction

2

of the machine. In order to change the position of the slide the same is provided with a pinion 13 to be turned by a handle wheel 11. The pinion coacts with a rack 14 stationary fastened to the frame 25 of the machine in the cross direction thereof. A central driving shaft 16 in bearings in the frame runs in the cross direction thereof through bearings 15 in the slide. The shaft is provided with a key way for a key in a chain wheel 17 or such like which chain wheel rotates with the shaft and is moved with the slide. A chain wheel 19 fastened to the roller 1 and a chain wheel 20 fastened to the roller 2 are driven by means of a common chain 18 from the chain wheel 17.

In the same way the underlying rollers 2 and 4 are arranged on a bottom slide 9a displaceable along guides 10a in the cross direction of the machine by means of a pinion 13a, and a central driving shaft 16a provided with a key way drives the rollers 2 and 4 by means of a chain 18a on corresponding chain wheels 17a, 19a, 20a. The central driving shafts 16, 16a coact by means of a gearing 21 the gears of which are secured to said shafts. At the one end of the machine a main driving shaft 22 is arranged coupled to the lower central shaft 16a by means of a gearing 23 and is driven by a pulley 24 or other driving means. The pinion 13a coacts with a corresponding rack 14a.

In the front of the rollers 1, 2, 3, 4 there is a guiding device 26 for the pasteboard sheet 5 and a feeding device 27 with adjustable feed rolls 28, 29. Some of these rolls are driven from shafts coupled to any of the driving shafts 16, 16a.

The sheet guiding device 26 consists of two shafts 32, 33, one above the other and running in the cross direction of the machine, each of them carrying a number of guide rolls; the shaft 32 with the guide rolls 34a, 34b, 34c, and the shaft 33 with the guide rolls 35a, 35b, 35c, 35d. The guide rolls are adjustable to different places along the shafts, being slidably mounted thereon, and the shaft 32 has adjustable bearings 36, so that the same can be adjusted towards the pasteboard sheet 5. The latter shaft preferably is driven, the rolls rotating with the shaft, but the shaft 33 preferably is stationary and the rolls thereon have free rotation on the shaft, being spaced, for instance, between collars adjustable on the shaft.

In the embodiment shown in the drawings the machine is built to make four parallel grooves in the pasteboard sheet at the same time, thus four aggregates A, B, C, D of groove making rollers are placed in a row in the cross direction of the ma-

chine as shown in Fig. 2. The three guide rolls 34a, 34b, 34c in front of them on the shaft 32 are arranged centrally between the four aggregates, and the four guide rolls 35a, 35b, 35c, 35d are placed each in front of one of the aggregates. According to the present invention the guide rolls 34a, 34b, 34c between the aggregates are arranged in such a way that the portions 5a of the pasteboard sheet between the grooving rollers are held in the shape of bows, whereas the guide rolls 35a, 35b, 35c, 35d straight in front of the aggregates are holding the sheet in the normal feed plane.

The two groove making rollers in each pair are adjustable towards each other. The one roller 2 (4) is arranged for rough adjustment and the other roller 1 (3) for fine adjustment.

The device for the rough adjustment consists therein as seen in Fig. 3, that the shaft pin 6a for the roller 2 is formed with an eccentric portion 36, on which the roller has free rotation. When the shaft pin is turned to different positions in the slide 9a by means of a handle 37, the centre position of the roller is changed and the roller is adjusted more near or more remote from the other roller in the roller pair. The device for the fine adjustment is arranged in the same way with the difference that a radially extending fork 38 fastened to the shaft pin 6 is substituted for the handle 37. Between the arms of this fork an eccentric disc 39 is turnable on a pin fixed to the slide. By turning the eccentric disc the eccentric portion 36 is turned and a fine adjustment of the roller is obtained.

It is of great importance that the cam 40 and the slot 41 of the coacting rollers are very carefully adjusted in reference to the thickness of the pasteboard sheet. Also a small erroneous adjustment in this respect will cause the bursting of the pasteboard in the groove on account of the low ductility of the pasteboard. To facilitate this adjustment and at the same time form the rollers to suit pasteboard sheets of different thickness the one roller which is intended for the slot is constructed of two discs 42, 43 with a space between them corresponding to the slot, as shown in the embodiment of Fig. 4. The discs are axially adjustable and in this way the space can be made more or less wide, and it has been proved that it is of advantage that there is no bottom in the space. The adjusting device can be of different art. In the embodiment shown the disc 42 has a screwthreaded bushing 44 integral for instance to the chain wheel 19a, and the disc 43 is screwed on the bushing and held in position by a nut 45.

In operation the pasteboard sheet is fed forward to the coacting rollers 1 and 2 between which the groove is rolled when the cam in the roller 1 presses the pasteboard into the slot of the roller 2 during the rotation of the rollers. In the embodiment shown the groove is rolled between this first pair of rollers to a part of its depth only, and will be rolled to full depth in the following pair of rollers 3, 4.

This is accomplished by adjusting the eccentric disc 39 and thereby turning the eccentric shaft portion 36 to a position such that the roller 3 is moved closer to its related roller 4 than the relative position of the rollers 1 and 2. Thus in passing between the first pair of rollers 1 and 2, a relatively shallow groove is rolled in the sheet while in passing the second pair of rollers 3 and 4 the groove is further rolled to the full depth desired.

The precaution of successively rolling the groove is however not sufficient to prevent the bursting of the material when the pasteboard exceeds a

certain thickness. To obtain a satisfying result it is necessary on account of the low ductility of the material to have a surplus of material at the side of the groove when rolling the same. On account of this the pasteboard sheet before it reaches the rollers is formed to a bow 5a between the roller aggregates A, B, C and D by means of the guide rolls 34a, 34b and 34c thus compensating the need of material for the groove and removing the difficulty on account of the low ductility. Preferably the bow 5a for the first pair 1, 2 of the rollers is formed so large that a smaller bow 5b is maintained for the second pair 3, 4 of the rollers where the groove is finished. In many cases it is however possible to finish the groove by means of one pair of rollers only, when the sheet has the said shape of a bow between the roller aggregates.

In order to complete the sheet with cross grooves the machine coacts with a machine of the like type placed after the first machine in the cross direction thereof, so that the sheet, having left the first machine will be fed sideways into the other machine where the cross grooves are made in the same way as is described above.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

35 What I claim is:

A machine for pressing grooves in pasteboard sheets comprising front rollers arranged in pairs, one roller of each pair being arranged above the other roller and the pairs of rollers being spaced in an axial direction, groove forming means on said rollers, pairs of upper and lower rear rollers arranged behind the front rollers, guiding means to give the sheeting a bow shape at points between and in front of the pairs of front rollers, the guide means being arranged to bow the sheet to such extent that after passing the front rollers the bow is maintained in a similar degree during passage of the sheet between the rear rollers, an adjustable slide supporting each upper front roller and the related rear upper roller, a lower slide adjustably supporting each lower front roller and the related lower rear roller, a drive shaft common to the upper slides, a drive shaft common to the lower slides and a driving chain extending over each drive shaft in each slide and over the related rollers.

ARTHUR KONRAD ANDERS JOHANSSON.
